UNITED STATES PATENT OFFICE.

WILLIAM T. BENHAM, OF RISING SUN, INDIANA, ASSIGNOR TO THE NYDIA BANK LOCK COMPANY, OF CINCINNATI, OHIO, A CORPORATION OF OHIO.

DIAL FOR COMBINATION-LOCKS.

1,174,011.

Specification of Letters Patent.

Patented Feb. 29, 1916.

Application filed February 28, 1913. Serial No. 751,248.

To all whom it may concern:

Be it known that I, WILLIAM T. BENHAM, a citizen of the United States, residing at Rising Sun, in the county of Ohio and State 5 of Indiana, have invented new and useful Improvements in Dials for Combination-Locks, of which the following is a specification.

My improvements relate to dials for combination locks, such as are ordinarily used 10 on safes, file cases and the like. These improvements are inexpensive, may be attached to combination locks already in use, and make it so easy for any one who knows 15 the combination to run it, with or without light, that it will prove a great advantage and convenience in all places where combination locks are now used, and will greatly extend their field of usefulness. Doors for 20 buildings or special rooms therein of all sorts may be fitted with such combination locks to great advantage.

My improvements consist fundamentally 25 of a rotatable dial having suitable gage notches, which notches may be either on the front or the back of the dial, and a plurality of indicators adapted to contact with these notches as they pass the indicators in the rotation of the dial at the will of the operator. These indicators are so constructed 30 as to be normally out of operative contact with the dial but held in contact by manual pressure and indicate by the sense of touch the passage over gage marks, in running the 35 combination. These improvements may be so constructed and applied to the ordinary dial as not to interfere with the running of the combination by sight, as at present.

The indicators are mounted upon or in 40 connection with the stationary dial rim, and have nothing to do with the rotation of the dial, nor have they any other function than to enable the operator to read the gage by touch or hearing, or both, according to the 45 way the indicator and gage may be constructed. If the dial is numbered at all, I prefer to number the gage marks each way from zero, as this is the method of counting and running any given combination used 50 with my improvements. Letters Patent Number 1,113,865, issued to me October 13, 1914, sets forth the details of this system of numbering dials. It will be understood that a system of elevations corresponding with

the depressions may be used in lieu of the latter, if preferred.

My invention is illustrated in the accompanying drawings, in which,—

Figure 1 is a front elevation of a lock dial, with my improvements applied to the under side of the dial, and a separate indicator each for zero, units and groups of ten units respectively. Fig. 2 is a rear elevation sectioned on the line $x-x$ of Fig. 3, through the rim, showing an under plan view of the dial and indicators. Fig. 3 is a partial cross section of the dial and rim showing one of the indicating levers in side elevation.

Referring now to the drawings, A, designates a rotatable lock dial having the usual 70 knob, a , and peripheral gage, a^2 , consisting of notches, a^3 , for given units of measure of a complete rotation—being hundredths in the present instance. The notches, a^3 , occupy corresponding and equi-distant radial 75 positions, arranged in consecutive series concentric with the axis of the dial plate, so as to be capable of contacting with a contact piece of a relatively fixed indicator, as presently to be explained. Each successive tenth 80 notch is extended radially inward into a corresponding annular space adjacent to that occupied by the hundredths notches, said extended notches thus constituting a new concentric series of graduations representing 85 groups of units 10, 20, 30, &c., of the original series, and the zero mark is further extended into a corresponding annular space adjacent to the latter. Each of the notches in these annular spaces is of such size and contour as 90 to cause the contact piece of the appropriate indicator (hereafter to be described) to “jump” into and out of the notches as the dial plate rotates, and thus indicate by the movement of the indicator the increments 95 of rotation appropriate to each indicator.

In the form of my improvement shown in Figs. 1 and 2, three indicators, U, T, Z, are employed, being levers of the first class extending laterally through a suitable recess, 100 20, in the rim, B, and mounted adjacent upon a common pivot, x , secured to the fixed rim, B, beneath the dial plate, A, so that their inner ends are held in a common radial relation facing respectively the annular series of notches formed as above described, at the underside of the dial plate corresponding with those upon the face. The

indicators are provided respectively with leaf springs, u^2 , t^2 , z^2 , bearing against the fixed rim, whereby the inner ends of the indicators are normally held out of contact with the dial. Each indicator is provided at its inner end with a contact piece, u' , t' , z' , respectively, adapted by its contour when the indicator is depressed at its outer extremity, to contact with the dial and "jump" in and out of the notches of its appropriate series against the force of the spring and thus indicate to the sense of touch each such notch in passing as the dial is rotated. The dial arbor, a^4 , is of the usual construction. In running any ordinary combination, all the indicators are used successively. For example—4 turns to right and to 20; 3 turns to left and to 13; 2 turns to right and to 11; 1 turns to left and to 50,—would be worked as follows: (1) press indicator Z and rotate the disk to right until the jump of the indicator contact piece into the notch, o , is indicated; then continue the rotation until three passing jumps are thus indicated and stop at the fourth; (2) then release indicator Z and press indicator T, and continue rotation of dial until two jumps of the indicator indicate 20—80, stopping at the latter; (3) release indicator, T, and again press indicator Z and rotate dial to left to o four times; (4) release indicator Z and again press indicator T, and continue left rotation until the indicator has contacted with the 10—90 notch; (5) then release indicator T and press indicator U and continue rotation until the indicator indicates three notches, stopping at third,—being 13, on the left hand count; (6) then release indicator U,

press indicator Z and turn the dial back to o , and turn the dial back to o three times, etc. 40

I claim as my invention and desire to secure by Letters Patent of the United States,—

1. In a combination lock, a rotatable dial provided with graduations upon its surface arranged in concentric circles representing, respectively, single units, uniform groups of units, and a starting point in the count, and a series of indicating devices arranged in line respectively with the graduations and adapted by manipulation to project an indicating point into contact with either set of graduations at will. 45

2. In a combination lock, a rotatable dial provided with graduations upon its surface, arranged in concentric annular spaces, and a corresponding series of indicating devices in line respectively with said graduations, and adapted by manipulation to project an indicating point into contact with either set 50 of graduations at the will of the operator.

3. In a combination lock, a rotatable dial having graduations on its underside, a chambered dial-seat having a correspondingly elevated rim and an indicating lever 55 projected radially through said rim into the chamber and adapted by external manipulation to project a contact point against the graduations.

In testimony whereof I have hereunto set 70 my hand in presence of two subscribing witnesses.

WILLIAM T. BENHAM.
